UNITED STATES PATENT OFFICE

JOSEPH C. GUSTAVESON, OF NEW YORK, N. Y., ASSIGNOR TO BESSA E. MADDEN, OF NEW YORK, N. Y.

AIR TREAD SOLE

Application filed February 6, 1929, Serial No. 337,962. Renewed August 22, 1931.

This invention relates to an improved air tread sole for shoes, and has for an object to provide a construction which may be permanently mounted in a shoe and positioned 5 to function so that the shoe will be efficiently ventilated throughout.

Another object of the invention is to provide an air tread sole for shoes formed with means actuated by the foot for positively 10 circulating air throughout the shoe during the walking operation.

A further object, more specifically, is to provide an air tread sole for shoes, wherein a 15 pair of flexible and resilient members are arranged in the shoe and formed with grooves and coacting beads for drawing in air at one end of the shoe and forcing the same out at another point.

In the accompanying drawings,—
20 Figure 1 is a bottom view slightly in perspective showing the upper part of an air tread sole embodying certain features of the invention;

Figure 2 is a perspective view of the lower 25 part of an air tread sole embodying certain features of the invention;

Figure 3 is a transverse sectional view 30 through a shoe disclosing an embodiment of the invention applied thereto;

Figure 4 is a fragmentary vertical sectional view through the forward part of a shoe and device embodying the invention.

Referring to the accompanying drawings by numerals, 1 indicates the bottom of the 35 sole of a shoe, and 2 the upper. These members may be of any usual or desired structure. The invention really consists in providing an air tread sole having a bottom tread member 3 and a top tread member 4.

The bottom tread member 3 may be made of 40 any flexible resilient material but is preferably made from rubber and is formed with a number of longitudinal extending grooves 5 extending from near the heel to near the 45 toe, as shown in Figure 2. At the heel portion of the member 3 a groove 6 is provided, said groove extending to near the arched portion of the member 3 and at that part merging into suitable grooves 6'. The radial 50 grooves 7 are arranged at the heel part and

are positioned to merge into groove 6. The grooves 5 at one end merge into groove 6 and at the opposite end into groove 8 which is spaced from the edge but conforms to the shape of the front part of member 3. A 55 number of auxiliary grooves 9 are arranged at the front, as shown in Figure 2. The top tread member 4 is provided with a number of projections or beads 10 shaped and positioned to fit into the various grooves 5, as 60 shown in Figure 3. The other grooves are left open or vacant, but the upper tread member 4 is provided with a number of apertures discharging or opening into the various 65 grooves 8 and 9. Preferably the lower tread member 3 is of one piece of rubber, while the upper tread member 4 is preferably formed with a rubber portion 12 having integral beads 10 and an upper or outside portion 15 of leather cemented or otherwise secured to 70 portion 12. If desired, the device could be placed loosely in the shoe, but preferably it is stitched therein by suitable stitching 14, as shown in Figure 3. In this way it is held 75 permanently and properly in place at all times and has the usual appearance of the interior surface of a shoe sole except for the apertures 11. When the device is in use air is drawn into the shoe around the heel, as the heel is elevated during the walking operation. This air finds its way into the grooves 80 6 and 7 and into the rear part of grooves 5. The air passes through the various radially-extending grooves 6' and 7. When the heel is forced downwardly as the person walks 85 the pressure thereof will depress the rear part of the upper sole member 4, and consequently, collapse somewhat member 3, while causing the beads 10 to move down to the bottom of their various grooves and in this 90 way squeeze or force the air from bottom members 3 and 4 at the rear part of the device. This results in the air being forced through the grooves 5 to the front of the shoe where the air is distributed by groove 85 and is eventually forced through the apertures 11 so as to ventilate the top and front part of the foot. As the air moves upwardly 95 around the front part of the foot it gradually finds its way backwardly and eventually 100

out between the lacings of the shoe or out through the front part around the ankle. Each time the heel is raised or lowered this action takes place. Consequently, air is 5 drawn in, forced to the front and then forced out through the apertures 11 to a position around the foot. It will be understood, of course, that only a small volume of air is taken care of at one time, but the continuous 10 movement during ordinary walking will provide a sufficient circulation of air to secure the desired result.

What I claim is:—

1. An air tread sole for shoes, comprising 15 a lower tread member having longitudinally-positioned grooves, an upper tread member formed with longitudinally-positioned beads superimposed on the lower tread member so that the said beads will fit into said grooves, 20 and means for securing the tread members together along their outer edges, whereby the central portions are loose in respect to each other, said central portions being yieldable under the action of the foot when walking, 25 whereby air is adapted to be drawn in at one end of the shoe when the pressure of the foot is removed from the upper tread member and expelled at the opposite end when the pressure of the foot is applied to said upper tread 30 member.

2. An air tread sole for shoes, comprising an upper tread member and a lower tread member, said lower tread member having grooves extending longitudinally thereof, a 35 connecting groove at each end merging into the longitudinal grooves, a plurality of auxiliary grooves at the top portion of the lower tread member arranged between said longitudinal grooves, said upper tread member 40 having apertures opposite said auxiliary grooves and radial grooves merging into the arc-shaped groove at the heel portion of said lower tread member said upper tread member having flexible beads positioned to fit 45 snugly into said longitudinal grooves when pressure is brought to bear on the upper tread member during the use of the shoe for causing air to move from the heel portion of the shoe to the toe portion.

3. An air tread sole, comprising a pair of superimposed members, the lower member having in its upper face a plurality of grooves extending from near the rear to near the front, said grooves at the rear opening to 55 the outer edge, and a top tread member conforming in general shape to the lower tread member, said top tread member being formed with a plurality of apertures adjacent the front and with depending beads fitting into 60 certain of said grooves, whereby the shifting of pressure on the upper tread member during the walking operation will cause a flow of air to pass through said grooves and said apertures for producing a ventilating 65 effect.

4. In a ventilated shoe, an inner sole consisting of two parts forming a bottom tread member and a top tread member, one of said parts having substantially equally spaced grooves formed in one of its faces extending longitudinally from near one end to near the opposite end and diverging at the front end and the other having beads formed on one of its faces, said beads being formed and positioned to match said grooves whereby air will 70 be intermittently forced longitudinally of the shoe during the use thereof, and means for holding said parts in assembled position. 75

Signed at New York, in the county of New York and State of New York, this 5th day of 80 February, A. D. 1929.

JOSEPH C. GUSTAVESON.
